UNITED STATES PATENT OFFICE.

CLIFFORD S. GOBY, OF CLEVELAND, OHIO, ASSIGNOR TO THE ENGINE HOLDINGS COMPANY, OF CLEVELAND, OHIO, A CORPORATION OF OHIO.

INTERNAL-COMBUSTION ENGINE.

1,100,656.

Specification of Letters Patent. Patented June 16, 1914.

Application filed August 23, 1909, Serial No. 514,098. Renewed November 4, 1913. Serial No. 789,224.

To all whom it may concern:

Be it known that I, CLIFFORD S. GOBY, a citizen of the United States, resident of Cleveland, county of Cuyahoga, and State of Ohio, have invented a new and useful Improvement in Internal-Combustion Engines, of which the following is a specification, the principle of the invention being herein explained and the best mode in which I have 10 contemplated applying that principle, so as to distinguish it from other inventions.

My invention relates to internal combustion engines of the four-cycle type, and its object is to provide a maximum economy of 15 construction with a maximum efficiency of operation.

The said invention consists of means hereinafter fully described and particularly pointed out in the claims.

20 The annexed drawings and the following description set forth in detail certain means embodying my invention, the disclosed means, however, constituting but one of various mechanical forms in which the principle of the invention may be applied.

In said annexed drawings: Figure 1 is a front elevation of the engine structure embodying my invention, showing the parts broken away to disclose the interior parts, 30 the lower portion of the frame being broken away. Fig. 2 is a partial end elevation and vertical transverse axial section, upon an enlarged scale, of one of the cylinders of the said engine. Fig. 3 is a horizontal section taken upon the plane indicated by line III—III in Fig. 2. Fig. 4 is an elevation of one of the valves detached from the valve chamber, and Fig. 5 is a horizontal section thereof taken upon the plane indicated by 40 line V—V in Fig. 4. Fig. 6 is an elevation of the interior valve-seat-forming wall of the valve chamber, detached, and Fig. 7 is a transverse section of same taken upon the plane indicated by line VII—VII in Fig. 6.

45 The frame A of the engine comprises a lower base portion A', consisting of a single casting, together with an upper capping portion A², also consisting of a single casting, and secured to the base portion by means of 50 suitable bolts and nuts a a, by means of which the said base portion may be readily attached or detached, as will be understood. The interior of the capping portion A² is provided with a plurality of cylindrical 55 seats a', Fig. 2, corresponding in number to

the number of cylinders which the engine includes, the particular engine illustrated in the drawing showing four cylinders. Placed in these seats are the cylinders B B, which are provided with bearing portions b, Fig. 2, 60 which fit snugly in said seats. The lower portion of the capping portion A² of the frame is formed with shoulders a³, four in number, and adjacent to the seat a'. The lower end portion of each cylinder is exteriorly threaded, and each threaded portion is engaged by a nut B', which bears against a washer b', interposed between the shoulder a³ and the upper end of the nut. Each cylinder is furthermore formed with a flange 65 b² which seats upon a similar flange a⁴ formed upon the upper edge of the capping portion A², as shown in Figs. 1 and 2, whereby the cylinders and capping portion may be secured to each other in any suitable well-known manner. That portion a⁵ of the capping portion A² is spaced away from the adjacent wall of the cylinder to form a water-jacket A³, Fig. 2. The head of each cylinder is made of double wall construction, 70 as shown in Fig. 2, whereby a water-jacket is formed for this portion of each cylinder. 75

Cast integral with each cylinder are two valve chambers C C, of circular cross-section, and having their axes parallel with the axes of the cylinders, the one chamber acting as a valve chamber for an inlet valve and the other as a valve chamber for the exhaust valve. Extending downwardly into these valve chambers are annular members C' C', 80 forming interior walls and spaced away from the adjacent wall of the valve chambers so as to form annular valve seats c c, Fig. 2. The upper ends of these members C' C' are formed with flanges c' c', whereby 85 they may be removably secured to the main body portion of the cylinders. These flanges are formed so as to provide an interior space c² for an oil chamber, and an opening c⁴ is provided, to which is attached an oil duct c⁴ 90 for providing oil to this chamber. A part of the valve chamber wall is made of double construction, so as to provide a water jacket C², communicating with the water jacket portion of the cylinder, and a suitable water inlet duct C³ is connected with this water jacket C². Each cylinder head is provided with an opening a⁶, and connected with a water outlet duct A⁴. 95

100 Each cylinder is provided with an open- 110

ing a^7 which serves as an inlet and exhaust opening, as shown in Fig. 3. Each member C' is provided with lateral openings c^8 , horizontally adjacent to the openings a^7 in the cylinders, and above and below these openings and upon the exterior of the said members are formed grooves c^9 for receiving packing rings c^7 . Below the openings c^8 and preferably formed integral with the member C' is a transverse partition c^8 , whereby downward communication with the interior of the member C' is prevented.

Inlet and exhaust ducts E are secured to the top of the members C' and communicate 15 with the interior thereof. Seated in each of the valve seats c are the annular admission and exhaust valves D D. Each of these valves is provided with lateral openings d^8 . The lower end of each valve articulates with 20 a connecting rod F, whose lower end is mounted upon a wrist pin g fixed to a crank G. These cranks are mounted upon a valve-operating shaft G', Figs. 1 and 2. To the outer end of this shaft G' is secured a 25 screw-gear g^1 , which engages with a second screw-gear g^2 fixed to the vertical shaft G², the lower end of which latter is provided with a screw-gear g^3 meshing with a screw-gear g^4 mounted upon the crank shaft G³ of 30 the engine. This crank shaft is connected with the connecting rods H secured to the pistons H' operating in the cylinders B, as will be readily understood. The screw gears are made of a size such that the exhaust and 35 admission valves will make one complete stroke for every four complete strokes of the pistons H'. The valve mechanism, together with its co-operating parts, forms the subject-matter of a divisional application No. 40 795,819, filed October 18, 1913.

In operation, the above described engine acts in the same manner as does the ordinary four-cycle type, the exhaust valve being closed when the admission valve is open. 45 After the admission takes place, a compression follows, and the admission valve closes, the exhaust valve being placed so as to be closed at this time also. The explosion now follows, with both exhaust and admission 50 valves closed, and at the end of the explosion stroke of the piston H', the admission valve will have reached the uppermost limit of its stroke. The exhaust now takes place, with the admission valve closed and the ex- 55 haust valve open, and following this, the admission takes place with the inlet valve open and the exhaust valve closed, as will be readily understood by those skilled in the art.

60 Having fully described my invention, what I claim therefore, and desire to secure by Letters Patent is:

1. In an internal combustion engine, the combination of a cylinder having cast there- 65 with a valve sleeve casing and a duct extend-

ing between the cylinder and the casing, a valve slidably mounted in said casing, a water jacket casing surrounding the valve casing and a portion of the cylinder, a second water jacket casing surrounding the remainder of the cylinder, said last casing being contracted at its lower end to form a close fit with the lower portion of the cylinder and being adapted to form a tight joint with said first water jacket casing, and rings threaded onto the cylinder for securing the same to the corresponding portion of the water jacket casing.

2. In an internal combustion engine, the combination of a plurality of cylinders, each cylinder having cast with the head thereof a valve casing sleeve and a water jacket casing surrounding said head and sleeve, said sleeve being spaced from said cylinder and communicating therewith through an integral duct, a water jacket casing inclosing the bodies of all of said cylinders and having contracted portions forming a close fit with the body of each cylinder, rings applied to the body of each cylinder and bearing against the portions of the water-jacket casing co-operating therewith, and a base casing section to which the water jacket casing is removably attached.

3. In an internal combustion engine, the combination of a plurality of cylinders each having cast with the head thereof a pair of valve casing sleeves and a duct extending from the head of each cylinder to and around both sleeves, a water jacket inclosing the head of each cylinder and its valve casing sleeves, a second water jacket casing inclosing the bodies of all said cylinders and having contracted portions forming a close fit with the body of each cylinder, a ring applied to the body of each cylinder and bearing against the portions of the water jacket casing co-operating therewith, and means for forming a tight joint between said water jacket casings.

4. In an internal combustion engine, the combination with a base portion forming a crank case, of an elongated capping portion secured thereto and having a plurality of constricted seats adjacent to said base portion and also having upon the further side of said seats from said base portion an enlarged chamber, of a plurality of cylinders in said capping portion and received in said constricted seats and making tight joints therewith and forming with said chamber a common water jacket, the heads of said cylinders being integral with the body thereof and having laterally projecting water jacket casings, the lower portion of which is adapted to engage the upper extremity of said capping portion and close such water jacket space.

5. In an internal combustion engine, the combination with a base portion forming a

- crank case, of a capping portion secured thereto and having a constricted seat adjacent to said base portion and also having upon the further side of said seat from said 5 base portion an enlarged chamber, of a cylinder in said capping portion and having its body portion received in said constricted seat and making a tight joint therewith and forming with said chamber a water jacket, 10 a valve casing integral with said cylinder but spaced from the wall thereof so as to overhang said water jacket, and a laterally projecting enlargement carried by the upper end of said cylinder body and adapted to engage the upper extremity of said capping 15 portion and complete such water jacket space.

Signed by me, this 10th day of August, 1909.

CLIFFORD S. GOBY.
